UNITED STATES PATENT OFFICE.

CHARLES J. HUBER, OF TAMPA, FLORIDA.

DISCOUNT-CARD.

SPECIFICATION forming part of Letters Patent No. 723,673, dated March 24, 1903.

Application filed August 28, 1902. Serial No. 121,806. (No model.)

To all whom it may concern:

Be it known that I, CHARLES J. HUBER, a citizen of the United States, residing at Tampa, in the county of Hillsboro and State of Florida, 5 have invented new and useful Improvements in Discount-Cards, of which the following is a specification.

This invention relates to discount-cards.

The card bears the names of business 10 houses—such as individuals, firms, corporations, &c.—and the rates of discount offered by each for cash payments by the holder of the card and also bears serially-arranged numbers for indicating the proportion of such 15 rates to which said holder is entitled. Upon the card is a space for the marking thereon of the name of the holder. In the present case the card is made in the form of a folder, one leaf of which has the name of the holder, 20 while the other is provided with the matter above alluded to; but of course the invention is not limited in this respect, for many variations may be adopted within the scope of the claims succeeding the description hereinafter made of one convenient form of the 25 article which I have selected for illustration.

The discount-cards may be and preferably are employed as follows: To each holder of a 30 pass-book is presented by a savings bank a card bearing his name, the name of the bank issuing it, and also the number of the pass-book. Upon one of the leaves of the card are placed the names of mercantile establishments, rates of discount which they allow for 35 cash payments, and serially-arranged numbers for indicating the proportion of such rates to which the holder is entitled, the proportion being regulated by the amount of deposit which the card-holder has at the bank, 40 such proportion or rates being increased as the deposit increases. This tends to encourage saving by the holder of the card and to increase the totals of the bank deposits, and the tradespeople by securing cash for goods 45 sold are much benefitted.

The card is shown in the accompanying drawings, forming a part of this specification, and in which—

Figure 1 is a face view of the card with the 50 leaves opened. Fig. 2 is a like view of the card with the leaves closed.

Like characters refer to like parts in both figures.

Referring to the drawings, the card is made in the form of a folder consisting of two leaves, 55 5 and 6, which may be of any suitable material, such as paper-board. These leaves are bound together in any suitable manner, so that they can be folded together to occupy a space approximating that of the average bank 60 pass-book. The back leaf 6 may be considered the main one, as it is adapted to bear the names of mercantile establishments and other matter used in connection with the discount system, as will hereinafter appear. 65

Upon the outer face of the front sheet or section 5 of the card may be printed or otherwise placed the following: "No. —. Issued by —, To —," the blank spaces to be filled, respectively, with the number of the 70 pass-book, the name of the bank issuing the same, and the name of the holder of the pass-book. The number of the card will correspond with that of the book, it being understood that one of these cards is presented to 75 each depositor with his book, or the outer face of said sheet 5 may be left blank and the data just mentioned written in.

The inner face of the sheet 5 has a long space in which may be printed the conditions 80 under which the card is issued, headed by the name of the bank and to be signed by the holder. These conditions may vary in different localities, and as they form no part of the invention they are not herein enumerated or 85 shown.

In some cases the sheet 5 may be dispensed with, and all or part of the matter appearing thereon can be placed upon the sheet 6, or if the sheet 5 be present it may bear matter other 90 than that mentioned, these being matters of taste.

Upon the inner face of the back or main sheet 6 appear at 7 the name of the mercantile establishments in the three-party compact or trading system. These may be arranged in any suitable manner. They are illustrated as being in column order longitudinally of the card.

In the present case the tradespeople, firms, 100 corporations, &c., under my coöperative system offer certain rates of discount for cash

payments for goods sold to the holders of the cards, and these rates of discount may be located in any suitable position; but in order to avoid confusion they preferably follow the 5 names of the respective tradespeople, firms, corporations, &c. Arranged in juxtaposition to these names are set forth the character of goods or merchandise sold thereby, so as to aid a card-holder in making purchases. This 10 advertises the merchants. The mercantile names are arranged centrally of the sheet on which they appear, and at opposite sides of the same are columns of figures each denoted by 8, arranged in groups, the numbers in 15 each group or line being in serial order. Over these columns of figures, respectively, appears the caption "Discount rates." These serially-arranged numbers indicate the proportion of the rate of interest to which 20 the holder of a card is entitled, and this proportion varies with the amount of deposit the card-holder has in bank. When his deposit is high, he is entitled to a greater proportion than when it is low. The figures in these 25 groups are shown as running from "1" to "4;" but this may, if desired, be materially changed. Each time a card-holder makes a deposit one number in a group is punched or otherwise marked or checked to indicate 30 the proportion of discount. Thus if the number "4" be punched it will indicate to the merchants that the holder is entitled to the full rate of discount offered by them. If the number "3" be punched, this shows that 35 he is entitled to three-fourths of such rate of discount, and so on. As soon as a card-holder makes a deposit one of the numbers in a group is punched or canceled in some other way. Let it be assumed that a card-holder has 40 purchased dry goods from the first merchant on the list, who allows six per cent. discount for cash. The merchant will require the discount-card, and on examining the last group of figures in which one of the latter has been 45 punched he will see that the number "2," for example, has been punched. This will indicate that the purchaser is entitled to two-fourths or one-half of the six per cent. discount. The rates of discount of the different 50 merchants may vary or possibly may be the same; but the proportion of the respective discounts will be governed by the amount of deposit the card-holder or depositor has in bank. The rows or groups of figures are pro- 55 gressively used, commencing naturally, with the first, and by looking at the last line in which a punched or otherwise-marked numeral appears the proportion of discount to which a card-holder is entitled can be seen at 60 once. The discount-card can be used with any savings-bank book, and it will last as long as the latter. It can be employed without changing the pass-books already in use in a bank. 65 One card only is necessary, regardless of the changes in balance by a depositor, the

fluctuations of these being indicated by the card.

The card is simple and can be produced in large lots at a low figure. 70

The use of the card is equally beneficial to bankers, depositors, and merchants. Depositors can secure substantial deductions on cash purchases by maintaining their accounts at a high figure. This increases the total de- 75 posits in bank. The bank will add to its de- 80 positors by the advertising received from the cards, and the latter will apply to the mer- 85 chants, who, in addition, receive cash for all sales made under the system.

The device possesses other advantages which are not necessary to set forth; but they will be obvious to prospective users of the same.

I do not, of course, limit the invention to the 85 kind of card nor to the arrangement nor character of matter thereon, for as to these and other matters material departures may be made.

The space above the names of the merchants 90 and their rates may be occupied by the letters A B C, &c., or other symbols may be em- 95 ployed, bracketed and entitled "Class," to indicate the merchants, which letters are fol- 100 lowed by the rates of discount offered by the respective merchants for cash payments.

Having described my invention, what I claim is—

1. A card of the class described bearing the names of business houses, symbols indicating 100 rates of per cent. associated therewith, and numbers arranged in groups, the same numbers being in each group and the numbers in each group being serially arranged.

2. A card of the class described bearing the 105 names of business houses, symbols indicating rates of per cent. associated therewith, and numbers arranged in groups in column order at each side of said names, the same numbers being in each group and the numbers in each 110 group being serially arranged.

3. A plurality of sheets bound together, one of which bears the names of business houses, symbols indicating rates of per cent. associated therewith, and numbers arranged 115 in groups, the same numbers being in each group and the numbers in each group being serially arranged.

4. A card of the class described bearing the names of business houses, symbols indicating 120 rates of per cent. associated therewith, and numbers of different values arranged in groups, the same numbers being in each group.

In testimony whereof I have hereunto set 125 my hand in presence of two subscribing witnesses.

CHARLES J. HUBER.
